[57] CLAIM

The ornamental design for a tadpole silhouette bait, as shown and described.

DESCRIPTION

FIG. 1 is a top plan view of a tadpole silhouette bait, showing our new design, the bottom being a mirror image thereof;

FIG. 2 is a side elevational view thereof;

FIG. 3 is an end elevational view thereof; and,

FIG. 4 is a top plan view of a second embodiment, the bottom being a mirror image thereof, with thickness the same as FIG. 2.
